UNITED STATES PATENT OFFICE

2,096,838

STERILIZER

Bunyan W. Baker, Charlotte, N. C.

Application November 18, 1935, Serial No. 50,449

2 Claims. (Cl. 21—93)

The object of my invention is to provide a novel device for effectively sterilizing mattresses by means of heat; and to provide a device of this character which is less expensive to manufacture and operate than the devices of the prior art. I attain these and other objects of my invention by the mechanism illustrated in the accompanying drawings, in which—

Figure 1 is a side elevation of the invention, with 10 the oven door closed;
 Fig. 2 is a similar view with the oven door open;
 Fig. 3 is a longitudinal section on line 3—3 of Fig. 4;
 Fig. 4 is a transverse section on line 4—4 of Fig. 2; and

Fig. 5 is a section on either of the lines 5—5 of Fig. 1, showing my preferred arrangement of V-shaped strip 16 on the edge of the door frame.

Like characters of reference designate like parts 20 in each of the several views.

Referring to the accompanying drawings, the letter I designates the sterilizer in its entirety; letter M designates a mattress; and letter P designates pillows; and A designates a standard "Arcola" furnace or stove. I provide a stove compartment 1, which has an opening 2 for a chimney 3. In this compartment is placed a standard "Arcola" furnace or stove A, with the smoke pipe running to the chimney. Above the stove 25 compartment 1 is a tin flue 4 having a slanting roof 24 which takes heat to the sterilizing compartment or oven 5 through opening 9 in end 8. The function of the slanting roof 24 is to cause the hot air to be evenly distributed in the oven. Were the roof of the flue just square, the heat 30 would travel upward until it struck the top and would then be directed along the top of the oven, instead of being distributed evenly through the oven as with the slanting roof. Both ends of the 35 sterilizing compartment or oven are open at 9 to permit the heated air to pass from flue 4 through the screen 10 (which is provided to keep out any dust or ashes that may arise from the stove or heating unit) into and through the oven 5 and thence into the end compartment 11, whence it 40 flows through the bottom compartment 12 and through the downflow pipe 13 to the chamber 7 beneath the "Arcola" furnace A, and thence to and upward through the chambers 13a within the 45 stove compartment 1 which surrounds the furnace or stove. The screen 10 is placed only in the passage between the flue 4 and the oven 5, the end member 8 below the screen being a solid wall as shown in Fig. 3.

50 The oven is provided with a door hinged to the

top by suitable hinges 15. The top front portion 6 of the air compartment 12 carries latches 17 which are slidably engageable over the edge of the door 14 when the door is in closed position. The door frame is provided with a longitudinally extending tin or metal strip 16, V-shaped in cross section. This V-shaped strip 16 is fastened on the bottom and both sides of the oven door frame. The bottom of the V is bolted onto the door frame, leaving the upper half of the side extending up 10 until the door 14 is closed. When the door 14 is closed it presses the free side of the V against the side that is fastened and thereby makes the V almost flat.

The sterilizing compartment or oven has a 15 series of L-shaped angle iron supports 18 on which are mounted lattice-work racks comprising the longitudinal bars 19 and cross bars 20, which are round in cross section, as shown in Fig. 2. These racks slide in and out on the supports 18 which 20 are fastened to the sides of the oven. The entire outside of the oven is preferably covered with sheet iron, which is then covered with thick asbestos paper.

I provide a suitable thermometer 21 and a metal 25 stem which goes through the metal front of the oven as at 22 in Figs. 1 and 2 of the drawings. The oven is supported on suitable legs 23 preferably of angle iron, as shown.

In operation the "Arcola" furnace A heats the 30 air in the surrounding chambers 13a and causes it to flow upward into the flue 4, whence by reason of the slanting roof 24 it is evenly distributed through the oven 5 and sterilizes the mattresses 35 M and pillows P or other bedding which may be placed on the racks 19, 20. The heated air, after passing over and through the oven, flows into the end compartment 11. Thence, as it cools, it will, as indicated by arrows in Fig. 3, flow through the chambers 12, 13 and 7, respectively, to the 40 chambers 13a surrounding the Arcola furnace in the stove compartment 1 to be re-heated and to again follow the same path through the sterilizer.

The door 14 is hinged and swung open to place the bedding on the racks, and the door is then 45 closed. When the door is closed its edge compresses the upper free side of the V-shaped metal device 16 and thereby makes a tight fit, as the V-strip takes up all slack or play in the door and makes the oven almost air-tight.

50 What I claim is:—

1. In an apparatus for sterilizing mattresses, the combination of a stove compartment having a stove, a vertically disposed flue adjacent and parallel with the stove compartment, an elongated 55

sterilizing compartment open at each end and in communication at one end with the aforesaid flue, a slanting roof on the flue extending to and terminating at the upper adjacent end of the sterilizing compartment to divert heated air even-
5 ly through the sterilizing compartment, a vertically disposed air return conduit at the opposite end of the sterilizing compartment, a horizontally-disposed bottom air chamber in communica-
10 tion with the said air return conduit, a down-flow chamber at the end of said bottom air chamber in proximity to the stove compartment and in direct communication with the horizontally-dis-
15 posed bottom air chamber, an air chamber dis-
posed under the stove and into which the afore-
said down-flow chamber opens, said last named air chamber being in communication with the vertically disposed flue adjacent the stove com-
partment, whereby the heat from the stove will
20 cause a continuous circulation of air through the sterilizing compartment, and a wire screen inter-
posed in the passage between the aforesaid flue and the aforesaid sterilizing compartment, the sterilizing compartment having a series of spaced
25 slidably mounted racks removably mounted in same.

2. In an apparatus for sterilizing mattresses, the combination of a stove compartment having a stove, a vertically disposed flue adjacent and par-

allel with the stove compartment, an elongated sterilizing compartment open at each end and in communication at one end with the aforesaid flue, a slanting roof on the flue extending to and terminating at the upper adjacent end of the sterilizing compartment, a vertically disposed air re-
5 turn conduit at the opposite end of the sterilizing compartment, a horizontally disposed bottom air chamber in communication with the said air return conduit, a down-flow chamber at the end of the aforesaid horizontally disposed bottom air chamber in proximity to the stove compartment and in direct communication with the horizontally-disposed bottom air chamber, an air chamber disposed under the stove and into which the 15 aforesaid down-flow chamber opens, said last named air chamber also opening into the vertically disposed flue which is positioned adjacent and parallel with the stove compartment, whereby the heat from the stove will cause a continu-
20 ous circulation of air through the sterilizing compartment and thence through the several cham-
bers described to the flue for reheating and return to the sterilizing compartment, and a wire screen interposed in the passage between the 25 aforesaid flue and the sterilizing compartment for the purposes described.

BUNYAN W. BAKER.
